TOY DOG

Frederick W. Mitchell, Culver City, Calif.

Application May 6, 1952, Serial No. 19,608

Term of patent 3½ years

(Cl. D34—2)

To all whom it may concern:

Be it known that I, Frederick W. Mitchell, a citizen of the United States, residing at Culver City, in the county of Los Angeles and State of California, have invented a new, original, and ornamental Design for a Toy Dog, of which the following is a specification, reference being had to the accompanying drawing, forming a part thereof.

Fig. 1 is a top plan view of a toy dog showing my new design;

Fig. 2 is a right side elevation of the same;

Fig. 3 is a front elevation of the same;

Fig. 4 is a left side elevation of the same;

Fig. 5 is a rear view of the same; and

Fig. 6 is an inverted plan view of the same.

I claim:

The ornamental design for a toy dog, as shown.
